FLOOR PLATE AND HANGER

Filed April 16, 1926

INVENTOR
WILLIAM R. REIN
By Cheever & Cox ATTY'S

UNITED STATES PATENT OFFICE.

WILLIAM R. REIN, OF CHICAGO, ILLINOIS.

FLOOR PLATE AND HANGER.

Application filed April 16, 1926. Serial No. 102,592.

This invention relates to floor plates and hangers usable in connection with electric wiring in buildings, and the general object is to provide means by which the time of installation may be reduced and the construction be strengthened and the appearance be improved.

One of the more specific objects is to provide a plate which may be applied to the subflooring of a building and which will allow for conduits and at the same time make it unnecessary for the workman, in order to do a good job, to saw a number of channels running at different angles in the floor.

Another object of my invention is to provide a relatively stiff thin plate with knock-out portions which plate is adapted to cover the opening in the sub-floor through which the electrical connections pass, the plate when in such position forming a complete cover for this hole so as to substantially prevent the passage of even relatively small objects therefrom, or which will prevent workmen from stepping through the hole, and which will provide a finished appearance to the job. Still another object of my invention resides in providing an entirely novel design of knockout or weakened portion in a plate-like member, which member may take the form either of a plate, as is illustrated in the drawings herewith, or may be formed as a part of an electric conduit box or the like.

Another object is to provide an improved type of fixture hanger and means by which it may be readily attached to the floor plate.

With the above and other objects in view, as will be apparent, this invention consists in the construction, combination and arrangement of parts, all as hereinafter more fully described and claimed.

I obtain my objects by the mechanism illustrated in the accompanying drawings wherein

Figure 1 is a sectional view through a floor, sub-floor and ceiling showing the present invention functioning in conjunction therewith.

Figure 2 is a plan view of the present invention illustrating the same cooperating with the sub-floor.

Figure 3 is a similar view of the floor plate forming a part of this invention; and

Figure 4 is a perspective view of the hanger.

Heretofore it has been the accepted standard practice, in bringing wire conduits

through the sub-floor and extending them between said sub-floor and the floor, to make a relatively small opening in the sub-floor with a number of slots radiating from and connecting with said opening and corresponding in number and direction to the number and direction of the leads or extensions desired. This necessitates a rather complicated sawing or cutting operation and is expensive when properly done. Frequently it is improperly done by roughly breaking or sawing a relatively large hole in the sub-floor and eliminating the aforesaid slots. This results in many objectionable qualities such as failure to pass inspection, noisy and weakened floors, etc.

It has also been the general practice heretofore to support the plate or outlet box of a ceiling fixture from a bar hanger interposed between and supported by adjoining joists which likewise has been found to be objectionable.

The present invention purposed to simplify and strengthen as well as eliminate the objectional features of the prior practices and to remove all incentive to the mechanic for doing this work improperly. This is accomplished by providing a floor plate which is designed to cover an opening in the sub-floor and be attached thereto by nails, screws or other suitable fastening means. This floor plate is provided with means whereby a number of conduits may be passed therethrough and extended in the desired directions between the floor and sub-floor. A hanger for the ceiling plate or outlet box is also so combined with the aforesaid floor plate that it is supported thereby and may be attached to the sub-floor.

Reference being had more particularly to the drawing, 10 designates the sub-floor laid on the joists 13 and provided with the furring strips 11 upon which is laid the floor 12. An opening 14 is placed in the sub-floor 10 through which the conduit 15 passes to enter and extend through the space 16 between the floor 12 and sub-floor 10. Below the sub-floor 10 and attached to the opposite edges of the joists 13 to those carrying the sub-floor 10 is the lathing 17 to which is secured the ceiling plaster 18.

The present invention comprises a relatively thin plate 19 of a size somewhat greater than that of the opening 14, which it is designed to entirely cover. At its edges the plate 19 extends over and bears on the

sub-floor 10 at the edges of the opening 14. Here the plate is provided with a series of apertures 20 for the reception of nails, screws or other suitable fastening means whereby 5 said plate is securely fastened to the sub-floor 10. Thus at the opening 14 is produced a substantially solid structure for all intents and purposes, the full equivalent of that portion of the sub-floor 10 removed to 10 create the opening 14. It is to be observed that the act of making the opening 14 in the sub-floor 10 simply calls for the sawing or cutting of a rectangular opening with no radiating slots as was heretofore required.

15 The plate 19 has a plurality of discs or knockouts 21 formed therefrom with weakened connections to the body of said plate whereby they may be readily removed individually and independently. Radiating from 20 each of these discs 21 is a series of tongues 22 formed from the plate 19 by cutting the same at the sides of each tongue. Thus at the point where it is desired to bring a conduit 15 through the plate 19 one of the discs 21 25 is removed, thus creating an opening 23 (Figure 1) in the plate through which one conduit 15 is passed.

After the conduit 15 is passed through the opening 23 the direction of the extension 30 thereof between the sub-floor and floor is determined and it is bent in the line of the tongue 22 most nearly approximating this direction. The free or inner end of this particular tongue 22 is bent downward to permit 35 the conduit to pass through or into the slot left by thus bending the tongue.

It is manifest that to all intents and purposes the plate 19 is substantially solid except where a conduit 15 passes therethrough 40 at which point it is only necessary to remove one of the discs 21 and bend down the proper tongue, the other discs and tongues remaining in place.

Cooperating with and partly supported by 45 the plate 19 is a hanger, shown in Figure 4, consisting of a pair of divergent arms 24 connected at their lower ends by the supporting bar 25. At their free ends the arms 24 are bent transversely and outwardly to create 50 the extensions 26 apertured at 27 for the reception of fastening means.

Adjoining its edges the plate 19 is pierced by the opposed rectangular openings 28 through which the free ends of the arms 24 55 are so passed that extensions 26 thereof rest upon the upper surface of said plate. When the arms 24 and extensions 26 thereof are so positioned said extensions are directed toward the edges of the plate 19 whereby fastening means passing through the apertures 60 27 also pass through said plate and enter the sub-floor 10 over which the extensions 26 are located. Thus the hanger is supported not only by the plate 19 but also by the sub- 65 floor 10.

The supporting bar 25 of the hanger has stud 29 secured thereto by means of the arms 30 formed on said stud 29 and embracing and engaging the bar 25. This stud 29 extends through the lathing 17 and ceiling 70 plaster 18 and is threaded at 31 for cooperation with a wing nut 32. A ceiling plate or outlet box 33 may be placed on the stud 29 and is clamped in place against the ceiling plaster 18 by the wing nut 32. In this manner the ceiling plate or outlet box together with any fixture that may be attached to the stud 29 is supported by the hanger and through it by the plate 19 and sub-floor 10. 75

In practice the mechanic cuts a substantially rectangular opening 14 in the sub-floor 10, and as this is a particularly simple operation it requires little or no skill and involves practically no expense. The floor plate 19 is then secured to the sub-floor 10 80 at the margins of the opening 14 completely covering said opening. When the floor plate 19 has been so positioned the appropriate discs 21 are removed or knocked out and the conduits 15 passed through the apertures 90 in said plate left by said removed discs. As the direction of the conduits 15 thus passed through the plate 19 can then be determined the corresponding tongues 22 are bent downwardly to permit the conduits to enter the slots or channels 23 left by the tongues and thence pass into the space 16 between the floor 12 and sub-floor 13.

The use of the foregoing structure in lieu 100 of the methods heretofore in vogue results in a workmanlike job by removing the incentives to the mechanic to do poor work. It maintains the strength of the sub-floor by covering the same with a strong plate and thus eliminates objectionable noises and 105 creaks. Furthermore no large uncovered openings are present in the sub-floor into which the feet and legs of persons may enter to their injury.

It will be appreciated that my invention 110 while particularly adaptable in connection with a floor plate is generically adaptable as a knockout design not only to floor plates but to conduit boxes or other members for enclosing electrical conduit installations. 115

Having thus described my invention what I claim as new and desire to secure by Letters Patent is:

1. A closure member of plate like formation having a series of apertures therein and slots radiating from each aperture in combination with a knockout closure for each aperture and a bendable closure for each slot formed from and attached to said plate. 120

2. A floor plate having a series of apertures therein slots radiating from each aperture and, in combination, knock-out closures for said apertures and integrally fastened tongue means for normally closing each slot. 125

3. A plate like partition member for elec- 130

trical installations having a central imperforate portion integral with the plate and having adjacent tongues substantially radiating from said integral portion, the outer ends 5 of said tongues being integral with the plate, a plurality of said tongues having a common knockout portion.

4. A partition plate for electrical installations comprising a plurality of slotted portions 10 angularly disposed with respect to each other and forming tongues, the outer ends of each tongue being integral with the plate, the adjacent tongues having a common knockout portion.

15 5. A partition member for electrical installations comprising a plurality of pairs of spaced apart slits formed in the partition

member and disposed at an angle with respect to each other and converging and meeting, the outer ends of the spaced slits being 20 integral with the plate, the meeting portion of said slits forming a common knockout portion for the slits.

6. A partition member for electrical installations comprising a plate having angularly 25 disposed channel like tongues integrally connected with the plate and adapted to be bent out of the plane of the plate, said tongues meeting and forming at their meeting point 30 a knockout portion.

In witness whereof, I have hereunto subscribed my name.

WILLIAM R. REIN.
